SAFETY DEVICE FOR STAMPING PRESSES
AND THE LIKE

Emil Sandel, St. Louis, Mo.

Application March 18, 1940, Serial No. 324,514

6 Claims. (Cl. 74—613)

My invention relates to a safety device for stamping presses and the like.

The object of my invention is to provide a press with an upwardly movable roller arm guard carrying a curtain shield unwindable from the roller arm guard to automatically prevent exposure of the hands of the operator to the dies, or other movable parts above the operator's table of the press, as well as the body of the operator from injury by broken parts thrown forwardly from the press.

A further object of the invention is to control the upward movement of the safety device directly from the crank-shaft of the press upon downward movement of the plunger, or cross-head thereof.

A further object of the invention is the provision of means for automatically rewinding the curtain shield instantly upon the ascending movement and for the return of the roller arm guard to normal non-protective position.

A still further object of the invention is to provide a safety device for presses which is simple and comparatively inexpensive in construction, and highly efficient in operation.

With the above and other objects in view, the invention consists in the novel features of construction, arrangement and combination of parts hereinafter more fully described and finally pointed out in the claims hereto appended.

Referring to the accompanying drawings:

Fig. 1 is a side elevation of a press equipped with a safety device embodying the features of my invention.

Fig. 2 is a front elevation of a press provided with my safety device.

Fig. 3 is a top plan view of a press provided with my safety device.

Fig. 4 is a detail of the roller arm guard with the curtain shield secured thereto.

Fig. 5 is a view showing the lever arms and curtain roller guard supported in its extreme elevated position.

In the drawings, I have illustrated a press designated, generally as A, and which includes the side frame members 1 and 1', the operator's table 2, the crank-shaft 3 and the plunger, or cross-head 4 controlled by the crank-shaft 3 for imparting reciprocating motion thereto.

In carrying out the invention, I employ a pair of lever arms designated 5 and 5'. The arms 5 and 5' are pivotally connected at their rear ends to the side frames 1 and 1' of the press, as at 6 and 6', respectively. The arms 5 and 5' project forwardly and downwardly from the pivots 6 and 6', respectively, to a point slightly in advance of the forward edge of the operator's table 2.

A suitable wheel 7 is suitably secured to one end of the crank-shaft 3 to rotate therewith. A suitable connecting rod 8 is pivoted eccentrically,

as at 9, at its upper end to the wheel 7 and the lower end thereof is shown as passing through a suitable eye-bolt, or equivalent member 10, which eye-bolt is pivotally secured to and projects laterally from the outside face of the lever arm 5 intermediate the ends thereof. The lower end of the connecting rod 8 is screw-threaded, as at 11, and is provided with one or more nuts 12 to serve as a stop to limit downward movement of the lever arm 5. The nuts 12 are disposed below the eye-bolt 10 so as to engage the lower face thereof for raising the lever arm 5 during upward movement of the connecting rod 8 during one-half revolution of the wheel 7 on the crank-shaft 3.

A suitable guide and supporting rod 13 is pivotally connected at its lower end, as at 14, to the lever arm 5' and projects upwardly therefrom. The upper end of the rod 13 passes upwardly through a suitable eye-bolt, or equivalent member 15, which is suitably secured to and projects forwardly from the side frame member 1'. The upper end of the rod 13 is screw-threaded, as at 16, and is provided with one or more nuts 17 acting as stop members to limit downward movement of the lever arm 5'. During upward movement of the lever arm 5', the rod 13 moves freely upwardly through the eye-bolt 15 which serves as a guide for the rod 13.

A suitable roller 18 is disposed between the forward ends of the lever arms 5 and 5'. The roller 18 is rotatably supported upon a shaft 19 which passes longitudinally and axially through the roller 18. The ends of the shaft 19 pass through openings in the free ends of the lever arms 5 and 5' and are supported thereby. The shaft 19 connects the lever arms 5 and 5' at their forward ends and is stationary relative thereto. The ends of the shaft 19 are screw-threaded and carry inner and outer nuts 20 and 20' to keep the lever arms 5 and 5' from spreading apart at their forward ends and to lock the shaft against rotation. The roller is provided at one end with an enlarged bore 21 to house a suitable coiled spring 22. The spring 22 is suitably anchored at one end to the shaft 19, as at 19', and at its opposite end it is suitably anchored to the roller 18, as at 18'.

A suitable flexible guard curtain, or shield 23 is suitably secured at its upper edge to the roller 18 and is normally wound a number of times around the roller. The lower edge of the curtain, or shield 23, which can be of suitable heavy fabric, leather or other suitable flexible material, is provided with a metal, or equivalent, reinforcement 24 having a plurality of openings 25 therein. A plurality of suitable hooks 26, or equivalent devices, are secured to the front face of the press adjacent and below the operator's table 2. The hooks 26 are adapted to pass through

the openings 25 in the lower edge of the curtain, or shield 23 for detachably securing the lower edge thereof to the press.

Operation

5 When the arm guard roller 18 is in its lowermost, or normal position, the plunger or cross-head 4 of the press is in its uppermost position. When the cross-head 4 starts to descend, the 10 wheel 7 rotates with the crank-shaft 3. Instantly, upon upward movement of the connecting rod, which is eccentrically connected to the wheel 7, the roller 18 is raised in an arcuate path due to 15 upward movement of the free ends of the lever arms 5 and 5'. The wheel 7 turns but one-half revolution during descending movement of the cross-head 4 and during this movement, the roller 18 has raised progressively to its uppermost position, as shown in dotted lines designated, generally as B in Fig. 1, with the descending movement of the cross-head 4 and stretched the curtain or shield 23 between the elevated roller 18 and the front of the operator's table 2 of the press. During the initial descending movement 20 of the cross-head 4 and the ascending movement of the roller 18, the operator's arm will be struck by the curtain on the roller and should his hand be exposed to the dies, the raising rotating roller 18 will cause the operator's arm to be rolled away 25 from the dies and at the same time elevated withdrawing his hand from danger.

At the same time that the roller is being raised and the curtain, or shield unwound therefrom, the coiled spring 22 is being wound up, and 30 instantly upon ascending movement of the cross-head 4, the coiled spring 22 will rewind the curtain on the roller 18 and pull the lever arms 5 and 5' downwardly to normal position, as shown in full lines in Fig. 1.

40 When it is desired to support the lever arms 5 and 5' and the roller curtain guard or shield in an extreme elevated position such, for instance, as when positioning dies, repairs, or for other reasons, the curtain or shield 23 is unhooked at 45 its lower edge from the hooks 26 and the lever arms 5 and 5', including the roller 18 with the curtain are raised to extreme upward position. When thus raised, a pin 27 can be positioned in an opening 13' in the guide and supporting rod 50 13 below the lever arm 5' to hold the same in its elevated position, as shown in Fig. 5, and the free edge of the curtain 23 can be attached to a hook 28 carried by the press frame to hold the free edge of the curtain in an elevated position.

55 The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, 60 may be made without conflicting or departing from the spirit of the invention within the scope of the appended claims.

What I claim is:

1. In a stamping press or the like having a 70 frame structure and an elevated crank-shaft supported thereby, the combination therewith of lever arms pivoted to and projecting forwardly

from the frame member, a wheel secured to one end of the crank-shaft, a rod eccentrically connected at its upper end to the wheel, a member having an opening therein secured to one of the lever arms, said rod passing through said opening and provided with a stop member below the opening, a shaft connecting the free ends of the lever arms and secured against rotation, a roller mounted on the shaft, a coiled spring encircling the shaft within the roller, said spring being secured at one end to the shaft and at its opposite end to the roller, and a flexible curtain guard secured at one edge to the roller and detachably connected at its opposite edge to the frame structure. 5

2. A device as defined in claim 1, including an apertured guide member secured to the frame structure, a rod like member pivoted at its lower end to the other of said lever arms, said rod like member passing upwardly through the apertured guide member, and a stop member carried by the rod like member above the apertured guide member. 10

3. In a machine having a frame structure and an elevated crank-shaft, the combination therewith of a lever arm supported roller guard curtain disposed normally in a lowered position in advance of the frame structure, the lower free edge of the guard curtain being detachably connected with the frame structure, and means actuated by rotation of one-half revolution of the crank-shaft to unwind and stretch the lever arm supported roller guard curtain upwardly to establish a curtain wall in front of the frame structure, and resilient means for automatically rewinding 30 the guard curtain instantly upon starting of the half revolution of the crank-shaft to lower the curtain wall. 25

4. A device as defined in claim 3, including means for holding the lever arm supported roller guard curtain in an elevated position in advance of the frame structure after the lower edge of the guard curtain is detached from its connection with the frame structure, and means for reattaching the free edge of the guard curtain in an elevated position to the frame structure. 40

5. In a machine having a frame structure and an elevated crank-shaft for actuating reciprocal means, the combination therewith of an eccentric disc secured to the crank-shaft, pivoted lever arms projecting forwardly and downwardly from the sides of the frame structure, a roller guard curtain carried by the free forward ends of the lever arms, said curtain being detachably secured at its lower free edge to the frame structure below the forward free ends of the lever arms, means for suitably connecting one of the lever arms with the eccentric disc for raising the lever arms to unwind and stretch the guard upwardly during one-half revolution of the crank-shaft, and resilient means for rewinding the roller guard curtain and lowering the lever arms instantly upon starting of the other half revolution of the crank-shaft. 50

6. A device as defined in claim 5, including means to limit downward movement of both lever arms, and means for holding the lever arms and guard curtain in an elevated position after the lower edge of the guard curtain has been detached from connection with the frame structure below the lowermost position of the lever arms. 60

EMIL SANDEL.
